METHOD OF MAKING SHOVELS AND THE
LIKEEdwin T. Nipher, Marietta, Ohio, assignor to
Ames Baldwin Wyoming Co., Parkersburg,
W. Va., a corporation of Delaware

Application April 4, 1933, Serial No. 664,349

9 Claims. (Cl. 76—113)

The object of this invention is to provide a method for the construction of a shovel or like blade having a handle-receiving extension involving few and simple operations. My invention will be well understood by reference to the following description taken in connection with the accompanying drawings, wherein:—

Fig. 1 is a front elevation of a completed shovel with the handle broken away;

Fig. 2 is a section on the line 2—2 of Fig. 1 on an enlarged scale;

Fig. 3 is a front elevation of the blade blank and the part which forms the extension prior to their being connected together;

Fig. 4 is a side elevation of the part forming the extension; and

Fig. 5 is a section on the line 5—5 of Fig. 3 on an enlarged scale.

Prior to my invention shovels have been formed as shown, for example, in the patent to Robertson 673,130, April 30, 1901, by butt welding into a suitable notch or recess in a blade-forming blank the ends of a pair of straps which serve for securing the handle and the blank has then been shaped to gage by a rolling operation. I propose to minimize or entirely eliminate the latter operation by providing a method of manufacture wherein a blade blank is utilized at least approximately of finished area and thickness.

Referring to the drawings, in Fig. 3 I have illustrated a blade blank proper 1 in the form of a suitable flat piece of steel of the desired thickness of the blade of the shovel and of such size as to permit it to be bent to the finished form shown in Fig. 1, although it may be slightly longer, as by the amount above the dot and dash lines 9 in Fig. 3, for reasons which will hereinafter appear. In the back or upper end of the blank is formed a recess or notch having the converging sides 11. The handle-forming extension is to be secured to the margins of this notch. Herein this extension is formed of two superposed pieces of metal of desired thickness, ordinarily somewhat lighter yet substantially like the thickness of the blade to provide a structure of adequate strength and these pieces (see Figs. 3 and 4) are provided with a relatively narrow strap-forming portion 13 terminating in end portions 15 which in the example shown are enlarged and resemble a spear-head at the end of a shaft corresponding to the strap portions 13 and having converging edges formed at an angle corresponding to the angle of the edges 11 of the notch in the blade blank. The enlarged head 15 has approximately the form of this notch and may be somewhat

shorter and is wider so that if moved downwardly into the notch from the spaced position of Fig. 3 the sides thereof would make contact with the side margins 11 of the notch before the head would bottom in the notch.

In the example disclosed the handle-receiving part is preformed as a unit to at least approximately its final finished form prior to attaching it to the blade blank proper 1. Herein (see Fig. 4) the strap portions 13 are shaped to approximately semi-cylindrical form and disposed at a desired angle relative to the head portions 15, the margins of which latter are disposed in face to face contact. The central portions of these heads, as indicated at 17, may be formed, as seen in Fig. 4, spaced from each other to form a frog which in the finished shovel (see Fig. 1) is disposed below the rear of the blade and receives the end of the handle. At least the lower portions of the straps 13 may be formed to present a tubular structure 20 and be welded together as indicated by dotted lines at 19 in Fig. 4.

To provide for securing such a handle-receiving part as described to the blade blank proper, which is of approximately finished thickness or gage 25 by means of an electric butt welding operation, I may secure together to welding the marginal portions of the enlarged heads 15 as indicated by the dotted lines 21 in Fig. 3 and the dark line similarly numbered in Fig. 5 where they pass the sides 11 of the notch in the blade blank. Alternatively I may locally shape edge portions of the parts to correspond in thickness one to another as herein by thickening or upsetting the margins 11 of the notch so that it is of substantially the thickness of the edges of the two heads 15, as seen in Figs. 2 and 5. Preferably I do both. The heads 15 of the handle-retaining part shown in Fig. 4 may then be inserted into the notch and advanced therein until the sides thereof contact with the margins 11. Because of the greater width of these heads as compared with the width of the notch the heads will not bottom in the notch and because of the somewhat greater depth of the notch the margins 11 will make contact with the sides of the head throughout the length of the latter. Effective contact between the parts to permit them to be heated to a fusing temperature for welding is thus provided and the joint is then completed by advancing the handle-receiving part 40 into the notch. The opposed margins of the parts are fused and burned away during this operation until the head is united to the blade blank throughout its margin. The upper edge of the enlarged head at the completion of the welding 45

will have advanced to the location of the dot and dash lines 9 in Fig. 3 and the extension of the blade blank above these lines may be trimmed away. The blade is then bent to the desired 5 finished form as, for instance, that indicated in Fig. 1, and the handle 29 may be bulldozed into the socket formed by the straps 13 so that its end enters the frog 17 at the center of the enlarged head portions and thus having an effective connection to the blade of the tool.

I am aware that the invention may be embodied in other specific forms without departing from the spirit or essential attributes thereof, and I therefore desire the present embodiment to be 15 considered in all respects as illustrative and not restrictive; reference being had to the appended claims rather than to the foregoing description to indicate the scope of the invention.

I claim—

20 1. The method of making a shovel or like blade having a handle-receiving extension which comprises forming a blade blank of substantially finished size and thickness and provided at the back with a tapering notch, superposing a pair 25 of extension-forming pieces having end or head portions approximately conforming in shape to said notch and of greater width, welding together the end portions along the sides thereof, entering the end portions in said notch and welding together 30 end portions and blade while advancing the former into said notch.

2. The method of making a shovel or like blade having a handle-receiving extension which comprises forming a blade blank of substantially 35 finished size and thickness and provided at the back with a tapering notch, superposing a pair of extension-forming pieces of like thickness to the blank having end or head portions approximately conforming in shape to said notch and of greater 40 width, welding together the end portions along the sides thereof, entering the end portions in said notch and welding together end portions and blade while advancing the former into said notch.

3. The method of making a shovel or like blade 45 having a handle-receiving extension which comprises forming a blade blank of substantially finished size and thickness and provided at the back with a tapering notch, constructing an extension-forming part from two superposed pieces 50 having tongues and enlarged heads, the latter approximately conforming in shape to said notch but of greater width, preforming said part to handle-receiving contour, welding together said heads at their sides, entering the head portions in 55 said notch and welding together head portions and blade while advancing the former into the notch.

4. The method of making a shovel or like blade 60 having a handle-receiving extension which comprises forming a blade blank of substantially finished size and thickness and provided at the back with a tapering notch having a margin thickened to correspond substantially to the combined thickness of the edge portions of the superposed pieces hereinafter recited, superposing a 65 pair of extension-forming pieces having end or head portions approximately conforming in shape to said notch and of greater width, entering said end portions into the notch with their sides opposed to the thickened margin thereof and welding together end portions and blade while advancing the former into the notch.

5. The method of making a shovel or like blade

having a handle-receiving extension which comprises forming a blade blank of substantially finished size and thickness and provided at the back with a tapering notch having a margin thickened to correspond substantially to the combined thickness of the edge portions of the superposed pieces hereinafter recited, superposing a pair of extension-forming pieces of like thickness to the blank having end or head portions approximately conforming in shape to said notch 10 and of greater width, entering said end portions into the notch with their sides opposed to the thickened margin thereof and welding together end portions and blade while advancing the former into the notch.

6. The method of making a shovel or like blade 15 having a handle-receiving extension which comprises forming a blade blank of substantially finished size and thickness and provided at the back with a tapering notch having a thickened margin, superposing a pair of extension-forming pieces having end or head portions approximately conforming in shape to said notch and of greater width, welding together the end portions along the sides thereof, entering said end portions 20 into the notch with their sides opposed to the thickened margin thereof and welding together end portions and blade while advancing the former into the notch.

7. The method of making a shovel or like blade 30 having a handle-receiving extension which comprises forming a blade blank of substantially finished size and thickness and provided at the back with a tapering notch having a thickened margin, constructing an extension-forming part 35 from two superposed pieces having tongues and enlarged heads, the latter approximately conforming in shape to said notch but of greater width, preforming said part to handle-receiving contour, entering said heads into the notch with 40 their sides opposed to the thickened margin thereof and welding together the heads and the blade while advancing the former into the notch.

8. The method of making a shovel or like blade 45 having a handle-receiving extension which comprises forming a blade blank of substantially finished size and thickness and provided at the back with a notch having converging edges, superposing a pair of extension pieces of substantially like thickness to the blade and having end portions approximately conforming to the shape of said notch and of greater width, locally shaping edges of the parts to correspond in thickness one to another, entering the end portions in the notch to oppose said edges and welding together end 55 portions and blade while advancing the former into the notch.

9. The method of making a shovel or like blade 60 having a handle-receiving extension which comprises forming a blade blank of substantially finished size and thickness and provided at the back with a notch having converging edges, superposing a pair of extension pieces of substantially like thickness to the blade and having end portions approximately conforming to the shape of said notch and of greater width, locally shaping edges of one of the parts to correspond in thickness to the other, entering the end portions in the notch to oppose said edges and welding together end portions and blade while advancing the former into the notch.

EDWIN T. NIPHER.
